TOILET SEAT

Herman F. Craig, Franklin, Ind.

Application March 2, 1935, Serial No. 9,034

5 Claims. (Cl. 4—245)

This invention relates to a sanitary toilet seat, and particularly to that type employing a pad of paper covering the seat, with the top sheet of the pad removable after use.

5 One feature of the invention resides in the arrangement of the supporting frame and pad, such that the separate sheets or layers will be maintained in their proper position and alignment. This is accomplished by recessing the frame or 10 providing an outer bead thereabout adapted to center the respective sheets or layers of the pad, with means associated therewith for holding them in position while permitting ready removal.

15 Another feature of the invention resides in the under-turned portions of the pad at either the front or back of the seat opening, such as will serve as additional protection and sanitation.

20 Still a further feature of the invention resides in the provision of forwardly extending tongues 20 of the paper pad seating in a recess of the frame for facilitating the gripping of the top sheet for removal. Other objects and features of the invention will be apparent from the accompanying drawing and the following description and claims:

25 Fig. 1 is a perspective view of the seat. Fig. 2 is a bottom plan view. Fig. 3 is an enlarged section taken on the line 3—3 of Fig. 1. Fig. 4 is an enlarged section taken on the line 4—4 of Fig. 1.

30 In the drawing there is illustrated a toilet seat frame 10 having the usual central opening and contour. The frame is relatively thin so as to support thereon a pad of paper sheets 11, said pad being cut to conform in shape and contour 35 to the frame so as to cover the upper surface thereof. The pad provides the relatively thin frame with substantial thickness, as well as providing a cushioning effect, as will be readily understood.

40 Surrounding the frame and pad contained thereon there is a raised bead or molding 12 which is undercut to provide an overhanging lip 13. Extending downwardly through the lip and removably mounted therein there are a plurality of 45 pins 14 having heads 15, said pins extending through perforations in the pad 11 with their lower ends supported in recesses provided in the frame.

50 The rear of the frame 10 is notched at 16 while the forward portion is notched at 17. These notches accommodate the paper tongues comprising the rear tongues 18 and the forward tongues 19. Said paper tongues are turned downwardly and laterally so as to extend along the 55 underside of the frame, as shown in Fig. 2. They

are loosely held in this position by brackets or screws 20.

The forward portion of the bead 12 is cut away to provide an opening through which tabs 21 of the paper extend to more readily permit gripping thereof by the user. It may also be noted that the brackets 20 loosely support the tongue so that in removing the sheets from the seat they will not bind at these points of support.

In use, it is contemplated that the toilet be 10 provided in the usual way with the frame 10 which will be a permanent fixture. The seat covering in the form of the paper pads 11 may then be mounted over the frame by means of a removable rear clamp 22, the tongues 18 and 15 19 being turned under and supported in place by the brackets 20. The outer edges of the pad are fitted under the lips 13 of the bead 12. The pins 14 may then be inserted about the bead 12, whereupon the sanitary seat is ready for use. 20

After use, the tab 21 provided on the top sheet is gripped to permit the top sheet of the pad to be removed. In removing this sheet, the tongues 18 and 19 are readily torn away from the brackets 20 with which they are loosely supported and the side edges of the sheet are torn from the pins 14, whereupon a fresh sheet providing a sanitary surface is in readiness for the next user. 25

Obviously, the method of use may be such that the top sheet is torn off immediately preceding 30 the use instead of thereafter.

While the invention has herein been specifically disclosed with respect to a toilet seat closed at the front, it is equally applicable to that type which is open at the front, in which event the 35 tabs 21 are eliminated, as well as the tongues 19.

The invention claimed is:

1. A sanitary toilet seat comprising a frame, a pad of paper sheets removably mounted upon said frame, and a raised bead formed about the periphery of said frame having an inwardly extending overhanging lip under which the lateral edges of the pad extend for maintaining the pad in juxtaposition relative to said seat. 40

2. A sanitary toilet seat comprising a frame, a pad of paper sheets removably mounted upon said frame, a raised bead formed about the periphery of said frame having an inwardly extending overhanging lip under which the lateral edges of the pad extend for maintaining the pad 50 in juxtaposition relative to said seat, and a plurality of removable pins spaced about said bead and extending through the lip and pad for locking the pad against movement.

3. A sanitary toilet seat comprising a frame, a 55

pad of paper sheets removably mounted upon said frame, each of said sheets having an inwardly extending tongue at the end portion thereof, said tongues being adapted to fold downwardly and forwardly to lie against the undersurface of the frame, and means for loosely locking said tongues in their underlying position.

4. A sanitary toilet seat comprising a frame, a pad of paper sheets removably mounted upon said frame, each of said sheets being provided with an inwardly extending tongue at the end portion of the seat, said tongues projecting downwardly to protect the inner edge of said frame, and an anchor member secured to the under-

portion of said frame for engaging and holding the free ends of the tongues in their downwardly extending position.

5. A sanitary toilet seat comprising a frame, a pad of paper sheets removably mounted upon said frame, each of said sheets being provided with inwardly extending tongues at the end portion thereof adapted to be bent downwardly to protect the adjacent edge of the frame, and a raised bead formed about the periphery of the frame to embrace said pad and maintain it in juxtaposition with respect to said frame. 5 10
